UNITED STATES PATENT OFFICE.

IRVING W. GREEN, OF CRANFORD, AND ALFRED H. INGLIS, OF UPPER MONTCLAIR,
NEW JERSEY, ASSIGNEES TO AMERICAN TELEPHONE AND TELEGRAPH COMPANY,
A CORPORATION OF NEW YORK.

DESIGN FOR A UNIVERSAL CASING FOR TELEPHONE SETS.

Application filed May 27, 1926. Serial No. 17,872. Term of patent 14 years.

To all whom it may concern:

Be it known that we, IRVING W. GREEN and ALFRED H. INGLIS, citizens of the United States, residing at Cranford and Upper Montclair, in the counties of Union and Essex, respectively, both in the State of New Jersey, have invented a new, original, and ornamental Design for Universal Casing for Telephone Sets, of which the following is a specification, reference being had to the accompanying drawing, forming a part thereof.

The drawing is a perspective view of a universal casing for telephone sets, showing our new design.

We claim:

The ornamental design for a universal casing for telephone sets, as shown.

In testimony whereof, we have signed our names to this specification this 26th day of May, 1926.

IRVING W. GREEN.
ALFRED H. INGLIS.
